UNITED STATES PATENT OFFICE

ROBERT O. BARNES, OF PHOENIX, ARIZONA

SAFETY RAZOR

Application filed March 19, 1929. Serial No. 348,306.

This invention relates to safety razors, and more particularly to the construction of a safety razor adapted to be made in the semblance of and folded after the manner of an ordinary pocket knife.

10 A further object of the invention is to provide a device of this character which may be employed as either a cross head or straight type of safety razor and in which the razor head will be securely held in either of its positions.

15 A further object of the invention is to provide a construction such that the razor head may serve as a means for supporting the blade while stropping the same and will secure the blade in either an extended stropping position or in a retracted shaving position.

20 A still further object of the invention is to provide a device of this character wherein the razor head is connected with the handle by a standard which is adjustable to various angular positions with relation to the handle.

25 A still further object of the invention is the production of a device of this character which may be readily and cheaply manufactured.

30 These and other objects I attain by the construction shown in the accompanying drawings, wherein for the purpose of illustration is shown a preferred embodiment of my invention and wherein:—

35 Figure 1 is a side elevation partly broken away of a safety razor constructed in accordance with my invention, the razor head being shown in the position which it occupies as a straight razor, the blade being shown in its projected or stropping position, in dotted lines;

40 Figure 2 is a side elevation of the razor being employed as an ordinary or transverse head type of razor, the dotted lines illustrating one of the adjusted positions which the head may assume with relation to the handle;

45 Figure 3 is a view similar to that of Figure 1 with the head folded into the casing and the nail file element extended;

50 Figure 4 is a rear elevation of the arrangement shown in Figure 3;

50 Figure 5 is a bottom plan view of the blank

employed in the construction of the guard plate;

Figure 6 is an edge elevation thereof;

Figure 7 is a vertical sectional view through the razor head;

Figure 8 is a section on line 8—8 of Figure 7;

Figure 9 is a section on line 9—9 of Figure 7;

Figure 10 is a sectional view similar to 60 that of Figure 7, showing the blade extended for stropping;

Figure 11 is a plan view of the blade.

Referring now more particularly to the drawings, the razor includes a handle 10, a 65 head 11 and a standard 12 for connecting the handle to the head. The handle 10 comprises spaced side plates 13 secured to one another at one end through a spacing block 14 and at one edge at the approximate center thereof by 70 securing elements 15 directed through a thickened central portion 16 of a spring element 17.

The ends of this spring element are free to move but the end of the spring element at the opposite end of the handle from the spacing block 14 contacts a pin 18 connecting the side plates 13. Intermediate the securing elements 15 and the pin 18, the outer face of this spring element has a hump or enlargement 19 forming a point at which the spring element may be engaged with a finger applying pressure to flex the same and cause an angular end portion 19 to be withdrawn from engagement with dentations 20 formed upon the hub 21 of the standard 12 which is pivoted 80 between the side plates adjacent thereto. This hub has an outstanding lug 23 which contacts the upper surface of the angular portion 19 and provides a limit to rotation of the standard when the standard is in longitudinal alignment with the handle.

The standard 12 is in the form of a narrow, flat strip projecting from one side of the hub 21 and has projecting from its opposite side edges pivot pins 24. The head 11 includes a 95 combined attaching and guard plate 25, one edge of which is dentate, as indicated at 26, and the ends of which adjacent this dentate edge are provided with pivots 27 adapted to engage a retaining plate 28. The guard plate 100

at its under surface and at its transverse center has a transversely extending shallow V-shaped groove 29. Resilient elements 30 confront this face and extend longitudinally thereof adjacent opposite ends of the groove, each of these resilient elements having formed in its upper surface or that surface confronting the guard plate a notch 31 which aligns with the groove 29.

These resilient elements may conveniently 10 comprise narrow extensions formed adjacent opposite longitudinal edges of the guard plate upon opposite transverse edges thereof which are reverted against the under face of the guard plate. The notches 31 receive the pivot pins 24 which, as will be noted from an 15 inspection of Figure 7, are slightly spaced from the end of the standard 12. The resilient elements 30 will yield to permit the end 20 portion 32 of the standard to engage in the groove 29 and will then maintain the engagement of the standard in this groove and thus hold the guard plate and accordingly the 25 razor head in the transversely disposed position upon the standard. The resilient elements 30 provide therebetween at opposite 30 sides of the groove 29 recesses which may alternately receive the standard, so that the razor head may be caused to lie at either side 35 of the standard and when in this position, the total thickness represented by the standard and razor head will be no greater than the normal thickness of the razor head. The 40 resilient elements will, of course, retain the head in either of the last named positions as well as in the transverse position with relation to the standard.

The upper surface of the guard plate has 45 extending upwardly therefrom a pair of spaced pins 33. The retaining plate consists of a flat plate having openings 34 through which the pins 33 may extend and having at its ends flanges 35 in which openings are formed for the reception of the pivots 27 of the guard plate.

These flanges extend slightly to one side 50 of the retaining plate and the pivot openings are formed therein and the opposite edge of the retaining plate has directed through the upper face thereof a pin 36 which extends 55 through the center of a bowed spring 37, the camber of which is upwardly disposed. This spring at its center and at its rear edge is provided with a depending arm 38, the lower end of which has a hooked terminal 39 underlying the spring. The pin is of such length 60 that it permits normal separation of the center of the spring from the retaining plate. When the retaining plate is swung to its closed position where it overlies the blade 40 and the guard plate, the hooked terminal of the flange of the spring may be engaged with the under face of the guard plate by applying pressure to the spring to flex the same. 65 Thus, the spring serves to resiliently force

the retaining plate toward the guard plate and against the blade 40 and to lock the retaining plate in its closed position, forming a resiliently engaged latch. The blade 40 has openings 41 at present shown as in the 70 form of notches produced in the ends thereof for passage of the pins 33 of the guard plate. This blade may be engaged with the guard plate either with the pins passed through these openings or with the rear edge of the 75 blade disposed against the pins. The first named position of the blade may be termed a shaving position and in this position the edge of the blade coacts with the dentate edge of the guard plate in the same manner that 80 the ordinary blade coacts with the guard plate of the usual style of safety razor.

In the last named position, the edge of the blade is projected sufficiently to permit engagement thereof with a strop or hone for 85 the stropping operation.

As will be noted from the foregoing, the blade can be arranged either transversely or longitudinally of the standard. Arranged transversely of the standard, as more clearly 90 shown by a comparison of the dotted and full line showings of Figure 2, the standard may be arranged at various angles with relation to the handle, so that a desired angle of the blade with relation to the handle may be obtained. 95 When employed in its longitudinal position with relation to the shank, the device is used either as a straight razor or for stropping by simply projecting the blade from its solid to the dotted line positions of Figure 1. When 100 in this position, and particularly when employed for stropping the razor, it will, of course, be obvious that some safeguard should be provided to prevent possible oscillation of the head upon the pivots of the standard. 105 While the resilient elements 30 will, to a great measure, prevent this, the stresses in stropping are particularly heavy and might possibly cause a deflection of the head, resulting in destruction of the strop or damage to the 110 blade. I accordingly project the ends of the side members, as indicated at 42, so that the lower end of the razor head lies therebetween when the shank is in its vertical position and the head is aligned therewith. It will also be 115 seen that when the standard is in the longitudinal position referred to it will lie in the recess formed between the members 30 which recess, as shown in Figure 1, extends longitudinally of the head. Thus, the head will 120 be very solidly held in position.

When aligned with the head, the standard may also be swung to cause the edge of this head at which the blade is exposed to lie between the side members 13 and be protected 125 thereby. Between its fully extended position and the completely folded position, the head, when aligned with the standard, is free from engagement with the side members and accordingly may be oscillated from its aligned 130

to its transverse position. Other toilet articles may be combined with the structure just described in the same manner in which they are combined with the ordinary jack knife. I have at present shown a nail file 43 as pivoted between the opposite ends of the side members from the standard and as coacting with the adjacent end of the spring. This nail file may be swung about its pivots to lie either flatly against the outer face of the spring or to extend outwardly from one end of the side members. The side members may, of course, have applied thereto an ornamental covering, such as bone, pearl or engraving metal, as generally indicated at 44.

It will be obvious that a device of this character may be very cheaply manufactured and because of its simple construction, may be conveniently manipulated in cleansing or in shifting of the device from one to another of its various positions.

It will also be obvious that the construction hereinbefore set forth is capable of a certain range of change and modification without materially departing from the spirit of the invention, and I accordingly do not limit myself to such specific structure except as herein-after claimed.

I claim:

1. In a razor of the type described, parallel side members secured in spaced relation to one another, a standard pivoted at one end between the side members and swingable about the pivot thereof from a position where it extends in the same general direction as the side members and lies therebetween to a position where it aligns with the side members and extends from one end thereof, means for securing the standard in the last named position or in positions intermediate to the first and last-named positions, said standard being in the form of a flat strip and having at its longitudinal edges adjacent its free end outwardly extending pivot elements, and a razor head comprising a guard plate and resilient elements adjacent the under surface thereof having guard plate confronting faces provided with notches for the reception of said pivots, the guard plate in alignment with the notches of the resilient elements having a groove for the reception of the end of the standard.

2. In a razor of the type described, parallel side members secured in spaced relation to one another, a standard pivoted at one end between the side members and swingable about the pivot thereof from a position where it extends in the same general direction as the side members and lies therebetween to a position where it aligns with the side members and extends from one end thereof, means for securing the standard in the last named position or in positions intermediate to the first and last named positions, said standard being in the form of a flat strip and having

at its longitudinal edges adjacent its free end outwardly extending pivot elements, and a razor head comprising a guard plate and resilient elements adjacent the under surface thereof having guard plate confronting faces provided with notches for the reception of said pivots, the guard plate having a groove for the reception of the end of the standard formed in alignment with the notches of the resilient elements, the side members having extended portions engaging opposite sides of the razor head when said head is aligned with said standard and the standard is in the last named position.

3. In a razor of the type described, parallel side members secured in spaced relation to one another, a standard pivoted at one end between the side members and swingable about the pivot thereof from a position where it extends in the same general direction as the side members and lies therebetween to a position where it aligns with the side members and extends from one end thereof, means for securing the standard in the last named position, said standard being in the form of a flat strip and having at its longitudinal edges adjacent its free end, outwardly extending pivot elements, and a razor head comprising a guard plate and resilient elements adjacent the under surface thereof having guard plate confronting faces provided with notches for the reception of said pivots, the guard plate having a groove for the reception of the end of the standard formed in alignment with the notches of the resilient elements, said resilient elements combining with the guard plate to produce a recess at opposite sides of the groove of the guard plate in which the standard may be disposed when the head is in alignment therewith.

4. In a razor of the type described, parallel side members secured in spaced relation to one another, a standard pivoted at one end between the side members and swingable about the pivot thereof from a position where it extends in the same general direction as the side members and lies therebetween to a position where it aligns with the side members and extends from one end thereof, means for securing the standard in the last named position, said standard being in the form of a flat strip and having at its longitudinal edges adjacent its free end, outwardly extending pivot elements, a razor head comprising a guard plate and resilient elements adjacent the under surface thereof having guard plate confronting faces provided with notches for the reception of said pivots, the guard plate having a groove for the reception of the end of the standard in alignment with the notches of the resilient elements, said resilient elements combining with the guard plate to form a recess at opposite sides of the notch of the guard plate in which the standard may be disposed when the head is in alignment therewith, the

side members having extended portions engaging opposite sides of the razor head when said head is aligned with the standard and the standard is aligned with the side members and extends outwardly therefrom.

5. A razor head adapted to be mounted on a standard comprising a guard plate having means whereby it may be connected with a standard, said guard plate having a dentate edge, a retaining plate pivoted to the guard plate adjacent the dentate edge thereof and swingable from a position where it is substantially perpendicular to the guard plate to a position where it overlies the guard plate and 10 confronts the upper surface thereof, a pin extending upwardly from the rear edge of the retaining plate, a bowed spring mounted upon said pin and having its concave face confronting the guard plate, and an arm 15 upon the spring at the center thereof having a hooked extremity for engagement beneath the lower face of the guard plate.

6. In a razor of the character described, a head comprising a guard plate, a pair of resilient bodies formed integral with the guard plate at two opposite edges thereof and extending in spaced parallel relation transversely of the under face of the same, each of said bodies having a notch formed in the plate 20 confronting face adjacent the transverse center of the plate and said plate having a groove formed transversely of the under face thereof between said bodies and in the same vertical plane as the notches, a supporting standard 25 for the head having one end positioned between said bodies for engagement in said groove, arms projecting from the longitudinal edges of said standard each engaging in one of said notches and bearing against the 30 under face of the plate, and shiftable means mounted upon the top of said plate for maintaining a blade in position thereon.

7. In a safety razor, a head comprising a guard plate having a groove formed transversely of the under face thereof and intermediate the ends, an elongated resilient member formed integral with each end of said plate and arranged to extend longitudinally of the under face thereof, said integral members being in spaced parallel relation and each having a notch formed transversely of the plate confronting face for coaction with said groove, a supporting standard for the head in the form of an elongated flat member having one end arranged between said resilient bodies and adapted to engage in said groove, arm members carried by the standard each engaging in one of said notches and held in frictional contact with the plate by the bodies, a blade retaining plate pivotally attached to the guard plate and overlying the same, a resilient member carried by the retaining plate, and an arm forming a part of said resilient member designed for frictional engagement 60

across the back of the guard plate to maintain the blade retaining plate in position.

In testimony whereof I hereunto affix my signature.

ROBERT O. BARNES.
